UNITED STATES PATENT OFFICE.

JOHN D. SMITH, OF POND HILL, PENNSYLVANIA.

IRONING-BOARD.

SPECIFICATION forming part of Letters Patent No. 637,039, dated November 14, 1899.

Application filed February 25, 1899. Serial No. 706,788. (No model.)

To all whom it may concern:

Be it known that I, JOHN D. SMITH, a citizen of the United States, residing at Pond Hill, in the county of Luzerne and State of Pennsylvania, have invented certain new and useful Improvements in Ironing-Boards; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to an improvement in ironing-boards; and it consists in a suitable clamp by means of which the improved attachment is secured in place, combined with a pivoted sleeve-board, which is adapted to be turned freely around and is provided with means to support it while in position, and a pivoted cross-piece to which the sleeve-board is pivoted, as will be more fully described hereinafter.

25 The object of my invention is to provide an attachment for ironing tables and boards for the purpose of enabling sleeves to be ironed upon their sides or edges, the sleeve-board of which is adapted to be rotated not only upon its own axis, but to swing through half a circle when it is to be turned back out of the way.

An attachment illustrating my invention is shown in the accompanying drawings, in which—

35 Figure 1 is a side elevation, partly in section; and Fig. 2 is a plan view of the same. Fig. 3 is a detail view showing the clamping devices, and in which no novelty is claimed.

A represents the two uprights of the clamp, 40 and to one of which the cross-piece B is pivoted. This cross-piece catches under the end of the ironing-board or a portion of the ironing-table and clamps the attachment in the usual well-known manner. The two uprights 45 A are rigidly secured together by the cross-piece C, and pivoted in the two standards above this cross-piece C is the cross-piece D, to which the sleeve-board G is pivoted. This sleeve-board G has a pivot I secured to one end, 50 and this pivot projects through the pivoted cross-piece D, and thus permits the sleeve-board G to turn freely upon its own axis, at

the same time that the cross-piece D is free to turn through half a circle, and thus enable the sleeve-board G to be brought into and 55 moved out of position, as may be desired.

The board G is given the shape shown, and in order to support it when turned upon either of its sides the two side pieces J are secured thereto, and which by resting upon the table 60 or ironing-board when one of the flat sides of the sleeve-board is turned upward forms a support for the sleeve-board, as shown. The sleeve-board is made sufficiently wide near its inner end to have one of its edges rest upon 65 the top of the table or ironing-board while the sleeve-board is being used in a vertical position to enable the edges of the sleeve to be ironed. No matter which edge of the board is turned upward a portion of its opposite edge 70 will rest upon the board or table, so as to prevent too great a strain being brought to bear upon its pivot. When this sleeve-board is to be brought into use, it is swung over the top of the table or board, and either its flat sides 75 or its edges can be brought into use, as may be desired, as the board can be freely turned upon its pivot. When the board is no longer needed, it is turned backward through half a circle by the pivoted cross-piece D turning 80 upon its pivots in the standards.

By means of an attachment as here shown the sleeves of garments can be perfectly ironed upon all sides, and the attachment can be quickly removed from the board or table when 85 not needed.

Having thus described my invention, I claim—

1. An attachment for ironing-boards consisting of a clamp by means of which the attachment can be secured to ironing boards or tables, a pivoted cross-piece journaled in the clamp, and a sleeve-board pivoted in the pivoted cross-piece, combined with means attached to opposite sides of the sleeve-board 90 for supporting the sleeve-board in position while either of its flat sides is in use, substantially as shown.

2. In an attachment for ironing boards and tables, a clamp and a pivoted cross-piece journaled in the clamp, combined with a sleeve-board which is pivoted in the cross-piece so as to be freely revolved, and which sleeve-board is made sufficiently wide near its inner 100

end to rest upon the ironing board or table, when either edge of the sleeve-board is brought into use, and the supports J which are attached to opposite sides of the sleeve-board so as to support it when either one of its sides is brought into use, substantially as set forth.

In testimony whereof I affix my signature in presence of two witnesses.

JOHN D. SMITH.
